MANUFACTURE OF STITCHED AND CEMENTED FOOTWEAR

Friedrich Holland, Brockton, Mass., assignor to
Compo Shoe Machinery Corporation, New
York, N. Y., a corporation of Delaware

Application September 26, 1935, Serial No. 42,180

4 Claims. (Cl. 12—142)

This invention relates to the manufacture of footwear, and more particularly to the lubrication, strengthening and protection of stitching used in such footwear.

5 A primary object of the invention is to provide an improved method for lubricating shoe stitching which is later to contact a coating such as pyroxylin cement or the like.

Further objects of the invention are to provide 10 an improved means for protecting shoe stitching against soiling during passage of the work through the factory, while assuring a firm bond between the stitched shoe parts.

Another object of the invention is to provide 15 a method of making a welted shoe wherein the outsole is affixed to the welt by means of cement, and wherein the inseam stitching is particularly adapted to provide and permit a strong and satisfactory bond between the shoe parts in its 20 vicinity.

Yet another object of the invention is to provide 25 a welted shoe wherein the welt is attached to the lasted upper by means of inseam stitching and the outsole is attached by means of cement and in which a lubricant is provided for the inseam stitching which has an affinity for or is compatible with the cement used to attach the 30 outsole.

Other objects of the invention will in part be 35 obvious and will in part appear hereinafter.

The invention accordingly comprises the several steps and the relation of one or more of such steps with respect to each of the others, and the article possessing the features, properties, and the 40 relation of elements, which are exemplified in the following detailed disclosure, and the scope of the application of which will be indicated in the claims.

For a fuller understanding of the nature and 45 objects of the invention reference should be had to the following detailed description taken in connection with the accompanying drawing, in which:

Fig. 1 is a plan view of a pre-formed and pre- 50 welted outsole treated in accordance with one form of the present invention;

Fig. 2 is a longitudinal sectional view taken along line 2—2 of Fig. 1; and

Fig. 3 is a fragmentary transverse sectional 55 view taken across the forepart of a lasted welted shoe constructed and treated in accordance with the present invention.

The principles of this invention are generally applicable in the manufacture of footwear where- 60 ever stitching is subjected to contact with adja-

cent coatings such as pyroxylin or like cement in the course of manufacture or in the finished shoe.

Thus, in Fig. 1, there is shown an outsole 10 having a welt 11 stitched thereto by means of stitching 12. Such a pre-formed and pre-welted 15 outsole is sometimes used, for example, in making men's sport footwear, and it is adapted to be ultimately attached to the lasted upper while leaving a wide extension edge which exposes the stitching 12 to view.

For ornamental purposes such stitching is generally made of white or lightly colored thread which gives a color contrast with the leather used in the welt. With such lightly colored threads, considerable difficulty is encountered in present- 15 ing them in a clean unsoiled condition in the ultimately finished shoe.

In accordance with the present invention such stitching 12 is not only kept clean during passage 20 of the work through the factory, but it is ultimately presented in a pure white condition, if white is the light color desired, which is not even shaded by the presence of wax or other lubricant. To this end, the stitching 12 is formed of wax 25 free thread which may be of linen, cotton, or other acceptable material. This thread is not waxed for lubricating purposes, as is generally done in leather sewing operations, but is instead, in a preferred example, wet or lubricated with liquid pyroxylin cement which is applied thereto 30 shortly before the stitching operation so that the thread will be wet, or, that is to say, sufficiently moist to enable the pyroxylin coating to act as a lubricant, during stitching.

The area in the vicinity of these pyroxylin ce- 35 ment coated stitches is now brushed over with a coating of pyroxylin cement, designated 13, which acts as a protective covering for the stitching during passage of the work through the shoe fac- 40 tory. In view of the use of this coating as a pro-tection, it is important that the stitching be wax-free as described, since wax interferes with or repels such cement and is liable to prevent the forming of an effective coating.

At this stage the stitched area of the shoe has 45 a protective coating of cement which is unitary or closely associated with the lubricating coating of cement occurring on the exposed portions of the stitching 12.

When the shoe is completed, or at any other 50 time when it is desired to free the stitching 12 from its protective coating, a suitable solvent is brushed over or otherwise applied to the coating 13 and the exposed portions of the stitches 12, sufficient solvent being applied to enable such 55

coating to evaporate or be rubbed entirely away. The solvent also removes the pyroxylin lubricant from the exposed portions of the stitching, leaving them in a natural brilliant white or uncolored 5 condition.

While pyroxylin cement comprises a preferred or highly satisfactory substance for use as the thread lubricant and coating material, it is contemplated that stitches may thus be protected 10 and later exposed to view through use of other suitable lubricants, so long as they are soluble, liquid, and compatible with, i. e. non-repellant to, the coating material. Various coating materials likewise may be employed, which should 15 preferably be soluble, together with the lubricant by means of some common solvent, although this is not strictly essential. The coating material may differ from the lubricant within these desired limits, or the same substance may be used for 20 lubricant and coating as in the preferred example given. Examples of suitable lubricating and/or coating materials are cellulose esters and ethers such as cellulose nitrates (including the preferred pyroxylin cement), cellulose acetate, the methyl, 25 ethyl, etc., ethers and the like. Viscose or plain cellulose in a suitable solvent might also be used for lubricating and/or coating, as well as glues, especially animal glues. It is believed that all 30 of these materials are compatible in the sense that any one may be used as a thread lubricant and any other as a stitch contacting coating with good results and without any mutual repulsion.

Suitable solvents for the above mentioned lubricating and coating materials will readily occur 35 to those skilled in the art; acetone is mentioned as one such solvent which is generally useful with the named cellulose compounds as well as others.

While the invention has thus far been described in connection with a pre-welted outsole, it will 40 be clear that it is applicable generally to shoe parts wherever stitching is intended to be protected against soiling and also wherever lubricated stitching is intended to contact a cement coating.

45 In Fig. 3, a further and highly useful application of the invention is indicated. Here, a welt shoe is made up by providing an insole 14 having the usual insole lip or rib 15 to which an upper 16 and a welt 17 are attached by stitching designated 112. This stitching is like that described in the first form in that it is made of wax-free linen or cotton threads which are lubricated with pyroxylin cement, or other suitable cement of the kinds described above, just prior to the inseam 50 stitching operation so that the applied cement is still wet enough to lubricate during sewing. When thus lubricated, these threads may, if desired, be made thinner than usual, say of five strand linen instead of seven strand, to permit closer inseam 55 trimming. After the inseam is sewed, the cement lubricant is allowed to set, and the inseam is thereafter trimmed. The use of pyroxylin or like cement as a lubricant is doubly advantageous in that it not only is superior to wax because of 60 its compatibility with the cement later used to join the outsole to the welt, but it permits an extremely close trim at the inseam because the thread also is strengthened by its cement coating, and forms a strong, tight seam wherein every 65 stitch is firmly anchored in place. It is of further advantage in cemented welt shoes because it enables the welt and inseam portions to be roughed 70 prior to cementing with reduced fear of weakening the joint at the inseam. That is, the shoe is 75 next reduced at the inseam and roughed at the

welt and inseam and these operations may be carried quite close to the stitching 112 since even if a strand or two or even a whole stitch of the latter is broken, the thread still will not pull out or run because it is firmly anchored in the shoe by means of its cement lubricating coating which has by this time set. 5

After the trimming and before the roughing operation, a suitable filler 18 is applied, and the required amount of this is much less than usual 10 because of the closeness of inseam trim available with the pyroxylin lubricated inseam stitches.

Next, an outsole 19 is affixed to the welt 17 and the inseam portion of the upper by means of a cement coating 113 which is applied between these 15 shoe parts. By virtue of the use of a pyroxylin or like cement lubricant, the bond between the outsole and upper is much stronger than could be obtained with ordinary wax lubricated thread since, as explained above, wax is incompatible 20 with and repels a cement. Also, the number of operations previously needed with conventional waxed thread is reduced, since heretofore the wax had to be stripped from the exposed inseam stitching whenever it was desired to cement in 25 the vicinity. The wax, too, would get on the hands of operators and thence to the sole and welt, where it acted to prevent formation of an effective cemented bond. All such difficulties are overcome by the present invention, and in addition, a stronger, better and more closely 30 trimmed welted shoe is provided.

The cement coating 113 preferably comprises those among the above recited examples of materials which have sufficiently strong cementitious properties, pyroxylin or other cellulose derivative cements being preferred for this purpose. The associated lubricant may comprise any of the herein mentioned examples or their like, all of which are compatible with any sole affixing 40 cement selected from among those described. The lubricant preferably should be cementitious when used at the inseam and like places, to secure the advantages of a firmer sewed bond wherein every 45 stitch is anchored in the leather.

It will be seen that there has been provided an invention which is well suited to fulfil its intended functions. Since certain changes in carrying out the above method, and certain modifications in the article which embody the invention 50 may be made without departing from its scope, it is intended that all matter contained in the above description or shown in the accompanying drawing shall be interpreted as illustrative and not in a limiting sense. 55

It is also to be understood that the following claims are intended to cover all of the generic and specific features of the invention herein described, and all statements of the scope of the invention which, as a matter of language, might 60 be said to fall therebetween.

Having described my invention, what I claim as new and desire to secure by Letters Patent, is:

1. A method of protecting shoe stitching from soiling, which comprises, providing a wax-free 65 thread, lubricating said thread with a liquid capable of forming a soluble coating, sewing shoe parts together with said thread while the lubricant is still wet, applying a soluble coating over exposed portions of said stitching, using said shoe 70 parts to make a shoe and, after the shoe is completed, dissolving said coating and the lubricant in the exposed portions of said stitching.

2. A method of protecting shoe stitching from 75 soiling, which comprises, providing a wax-free

thread, lubricating said thread with a liquid cement comprising a cellulose derivative, sewing shoe parts together with said thread while the cement lubricant is still wet, and applying a coating of such cement over exposed portions of said stitching.

3. A method of protecting shoe stitching from soiling, which comprises, providing a wax-free thread, lubricating said thread with a liquid cement comprising a cellulose derivative, sewing shoe parts together with said thread while the cement lubricant is still wet, applying a coating of such cement over exposed portions of said stitching, using said shoe parts to make a shoe

and, after the shoe is completed, dissolving said coating and the lubricant in the exposed portions of said stitching.

4. A method of protecting shoe stitching from soiling, which comprises, providing a wax-free thread, lubricating said thread with a liquid pyroxylin cement, sewing shoe parts together with said thread while the cement lubricant is still wet, applying a coating of pyroxylin cement over exposed portions of said stitching, using said shoe parts to make a shoe and, after the shoe is completed, dissolving said coating and the lubricant in the exposed portions of said stitching.

FRIEDRICH HOLLAND.
